UNITED STATES PATENT OFFICE.

CARLOS BAILEY HAYNES, OF NORTH ADAMS, MASSACHUSETTS.

STARCHING AND TENTERING MACHINE.

SPECIFICATION forming part of Letters Patent No. 320,249, dated June 16, 1885.

Application filed March 18, 1884. (No model.)

To all whom it may concern:

Be it known that I, CARLOS B. HAYNES, of North Adams, State of Massachusetts, county of Berkshire, have invented a new and useful 5 Improvement in Starching and Tentering Machines; and I do hereby declare that the following is a full, clear, and exact description of the invention, which will enable others skilled in the art to which it appertains to make and 10 use it, reference being had to the accompanying drawings, forming a part thereof.

My invention relates to starching and tentering machines, and has for its object the provision of a machine so constructed and arranged as to enable a single person to control and operate the entire apparatus while occupying one seat and without removing therefrom. The location of this seat with relation to the other parts of the machine is such as to 15 enable the operator not only to control the machine as above stated, but also to inspect the various operations of the parts, and to see, without removing from the seat, that everything is in working order and is working properly.

The invention will be understood from the following description, and pointed out in the claims.

The accompanying drawings illustrate what 30 I consider the best means for carrying my invention into practice.

Figure 1 is a side elevation of a portion of a starching and tentering machine with my invention applied thereto. Fig. 2 is a rear elevation of the same. Fig. 2^a is a detail showing the ends of the starch-pipes on the inside of the cloth. Fig. 3 is a detail showing the cleaning-brush and serimp-roller. Fig. 4 is a detail showing the small stretching-rollers. 35 Fig. 5 is a plan view of the device illustrated in Fig. 1.

Similar letters of reference indicate corresponding parts in all the figures where they occur.

45 Z is the fixed frame of the machine, and Z' the support for the starch-barrels. Upon an extension, Z², of the frame Z the cloth-roller A is placed, upon which the cloth is wound. Friction-rollers B, also held in the frame or 50 extension Z², guide the cloth in its travel toward the starching-rolls and tentering device

and apply the proper tension thereto. In standards of the frame Z are placed the starching-rolls D D, held in suitable bearings, as shown. On the outer end of the shaft of one 55 of these rolls D is placed the power-wheel or band-pulley D', by means of which they are driven. On the opposite side of the rolls D from that on which the cloth enters them is arranged the tentering-frame Z², over the rollers z z on which the tentering-chains F pass. This tentering-frame is of the same construction as that shown in English Patent No. 6,104 of 1831, so that the distance between the tentering-chains can be varied, as set forth in said 65 English patent; but in applicant's device the long shaft K is applied to make the frame adjustable from the operator's seat, as will be hereinafter more fully set forth.

To the front of the standards of the frame Z, 70 in which the starch-rolls are held, are secured brackets C², having secured upon them the cleaning-brush C and serimp-roller C', over which the cloth is caused to pass before entering between the starch-rolls. The brackets 75 C² can be set at any height upon the standards, and thus bring the brush and roller into any desired relation to the starch-rolls vertically. This adjustment can be accomplished by removing the screws by which the said brackets 80 are secured upon the frame and reinserting them at the desired height. After passing between the starch-rolls, and before reaching the tentering-chains, the cloth passes between the selvage-rollers E E, where the selvage edges 85 are straightened. These rollers E E lie close together and press and straighten the selvage edges between them.

Z² is a support upon which are placed the starch-barrels M M, which have discharge-tubes N N extending to the starch-rolls D and delivering the starch upon them or upon the cloth immediately in front of them. As shown in Fig. 2^a, the tubes N N drop the starch upon the goods immediately in front of the rolls; but 90 it will be understood that by properly bending them they may be made to deliver the starch upon the rolls themselves. The discharge tubes or conductors N N are fitted with cocks or valves O' O', which have long handles O O.

Upon the platform P' of the extension Z² of

the frame on which the rollers A B are held is placed the seat P, of a length about equal to the width of the machine. Upon this seat the operator sits, and it is evident that the position he thus occupies enables him to inspect the operation of the entire apparatus. He can see that the cloth is feeding evenly over the rollers B, brush C, and scrimp-roller C', and entering between the starch-rollers squarely 10 and evenly without wrinkle or fold. He also can see that the starch is being properly delivered to the starch-rolls, and that the operations of the tentering device are being properly performed. By reason of the long handles O O he is enabled without leaving his seat to control the cocks O' O', and the flow 15 of the starch through them, and by means of mechanism to be explained he can also control the width of the tenter-chains from each 20 other and this consequent stretching action upon the cloth they are conveying. For this purpose the tenter-chains are held upon rollers z z and moved laterally by a screw-shaft, G, threaded in opposite directions from about 25 mid-length outward, so that upon turning it in one direction it will cause the tentering-chains which it carries to be spread apart, and being turned in the opposite direction to be drawn together. This screw-shaft and its operation 30 in increasing or diminishing the distance between the tentering-chains is already well known, as may be seen in the English patent above referred to, and need not be more fully described here, as I do not claim it alone.

35 Upon one end of the shaft G, I place a bevel-pinion H, and connect with it a small gear, H', attached to the end of a bar or shaft, K, which extends in an upwardly-inclined position, and

is held by suitable bearing L on the standard of the frame Z, in which latter the starch-rolls 40 are held. The upper end of the shaft K is provided with a hand-wheel, I. This hand-wheel I lies close enough to seat P to enable the operator to take hold of and turn it without leaving the seat. This gives the operator 45 control of the tentering-chains F while sitting upon the seat P. It is thus seen that the operator can inspect and govern the entire apparatus from one point. This makes it possible to dispense with the services of several 50 persons, which have heretofore been employed upon a machine of this character, and commit the entire management of the apparatus to a single person.

Having thus described my invention, what I 55 desire to claim and secure by Letters Patent is—

1. The combination, with the rolls D, fixed frame Z, extension Z', platform P', and seat P, of the starch-barrels M, the conductors N, 60 cocks O', and long handles O, and means for supporting barrels M and for operating rolls D, as set forth.

2. The combination of the rolls D, the seat P, located in front of said rolls, the starch-barrels M, conductors N, cocks O', and long handles O, as set forth, and the screw-shaft G, 65 gears H and H', shaft K, hand-wheel I, and supports for the starch-barrels and seat, as set forth.

In testimony that I claim the foregoing I append my signature.

CARLOS BAILEY HAYNES.
